UNITED STATES PATENT OFFICE

FRANCIS MAXIME CROSSMAN, OF PARIS, FRANCE

DRYING OR CARBONIZING MACHINE

Application filed May 18, 1929, Serial No. 364,303, and in Great Britain May 24, 1928. *

The present invention relates to improvements in drying or carbonizing apparatus of the type in which a number of trays for supporting the material to be dried or carbonized 5 are hinged at one edge, and are mounted to be rotatable about a central supporting axis, being normally held horizontally by supporting rails which are interrupted at one point to allow the trays to swing down and 10 discharge their contents.

According to this invention a central driving shaft is adapted to support a skeleton cellular framework, the floor of each individual cell being in the form of a tray pivoted on one radial edge.

The invention is more particularly described with reference to the accompanying drawings in which:—

Figure 1 is an elevation of one form of 20 construction of drying or carbonizing apparatus partly in section.

Figure 2 is a plan view on the line 2—2 of Figure 1.

Figure 3 is an under plan view of the trays 25 with their supporting rail.

Figure 4 is a partial top plan view of the trays.

Figure 5 is a partial perspective view of the trays.

Figure 6 is a diagrammatic view showing 30 angularly spaced discharge areas from one tier to the next.

Figure 7 is a detailed plan view of a tray.

Figure 8 is a sectional elevation on the line 35 8—8 of Figure 4.

Figure 9 is a sectional side view on the line 9—9 of Figure 2.

Figure 10 is a sectional elevation on the line 40 10—10 of Figure 4.

Figure 11 is a sectional elevation side view on the line 11—11 of Figure 2.

The carbonizing or drying apparatus consists of a cylindrical chamber 1 provided 45 at its top with an opening having a distributor 2 for feeding material, such as pulverulent material to be carbonized, to tiers of trays *a*, *b*, *c*, *d*, *e*, *f*, *g*, *h*, *i*, *j*, *k*, *l*, *m*, *n*, *o*, *p*, supported by a central shaft 15, and from the 50 lower tier *p* of which the material is dis-

charged into the hopper 3 in the base of the casing.

The lower end of the casing 1 is closed by means of a conical end 5 provided with a conduit 4 connected to a source of hot gas, superheated steam or the like drying or carbonizing agent, which passes up through the material on the tiers of trays *a*, *b*, *c* . . . *o*, *p*, and escapes at an opening arranged in the top 6 at the top of the chamber 1. 60

Each tier of trays, *a*, *b*, *c* . . . comprises a frame-work 14 supported from a shaft 15 and having annular rigid partitions 13, 19, and rigid radial partitions 17, 18. To the edges of certain of these radial partitions are 65 hinged perforate trays 20 (Fig. 7) by means of hinge pins 21. These trays are provided with perforations 24 and have rollers 23 on their under surfaces adapted to co-operate with a fixed circular supporting rails 8, so that the trays are normally held horizontal 70 for the support of the material upon them, but will drop down to a vertical position as shown in Figure 11, when a gap in the rails 8 occurs. 75

The leading edge of the gap in the rail 8 is preferably provided with a ramp rail extension 25, so that the trailing edge 22 of the trays will be raised from its dropped position smoothly again to the horizontal position 80 as shown in Figure 9.

Material therefore, falling within the compartments or cells of the frame work 14 and supported by the trays 20 will be carried round by the shaft 15 in its rotation 85 substantially a complete revolution when a gap will occur in the rail 8 allowing a tray 20 to fall down and discharge its material to a tray lying in the tier *b* next below it. The material will then be carried round on 90 its tier also almost a complete revolution until another gap in the supporting rail for the trays of tier *b* occurs when the material will then be discharged on to the tier *c*. These discharge areas will be displaced by 95 say substantially 340° angularly from one another, as for instance, shown diagrammatically in Figure 6 where 9^a, 9^b, . . . 9°, 9^p, indicate the discharge areas of successive tiers. 100

July 1, 1930.
